KNITTED FABRIC

Vincent Lombardi, Garden City, N. Y., assignor to
 Lombardi Knitting Machine Co., Inc., New
 York, N. Y., a corporation of New York

Application June 23, 1939, Serial No. 280,795

7 Claims. (Cl. 66—201)

This invention relates to knitted fabric, and more particularly to design fabrics.

An object of the invention is the provision of knitted fabric of such character that unusual and distinctive design effects may be secured.

Another object of the invention is the provision of knitted fabrics which will have a particularly attractive appearance from a variety of standpoints.

Other objects of the invention will in part be obvious and will in part appear hereinafter.

The invention accordingly comprises an article of manufacture possessing the features, properties, and the relation of elements which will be exemplified in the articles hereinafter described and the scope of the application of which will be indicated in the claims.

For a fuller understanding of the nature and objects of the invention reference should be had to the following detailed description, taken in connection with the accompanying drawings, in which:

Figure 1 is a somewhat diagrammatic rear view of a portion of one form of fabric embodying the invention;

Fig. 2 is a reduced scale view illustrating the appearance of the front of a partly overlapping portion of the fabric of Fig. 1;

Fig. 3 is a reduced scale view illustrating the appearance of the rear of a partly overlapping portion of the fabric of Fig. 1;

Fig. 4 is a view similar to Fig. 1 showing a modified form of fabric;

Fig. 5 is a similar view showing a further modification;

Fig. 6 is a similar view of another form of fabric embodying the invention and shown in the process of formation;

Fig. 7 is a diagrammatic view of fabric of Fig. 6;

Fig. 8 is a larger scale, more detailed view of the portion of the fabric outlined by dot-and-dash lines in Fig. 7;

Fig. 9 is a somewhat diagrammatic front view of fabric embodying the invention in certain of its aspects; and

Fig. 10 is a similar view illustrating a somewhat modified form of fabric.

This application is a continuation in part of the co-pending applications of Vincent Lombardi, Serial No. 135,635, filed April 8, 1937, now Patent 2,119,793, and Serial No. 230,408, filed September 17, 1938.

While in certain cases it is desirable to provide design fabrics wherein what is commonly known

as the "front" of the fabric is utilized as the exposed portion of a garment or other article, and in other cases it is desirable to provide design fabrics wherein what is commonly known as the "rear" of the fabric is utilized as the exposed portion of a garment or other article, and while many fabrics having attractive designs on either the front or the rear of the fabric have been provided; there are many instances in which it is desirable to have a fabric wherein attractive designs appear on both sides of the fabric, so that either side may be utilized as the face of a garment, and so that a fabric may be turned over in forming different portions of a garment without detracting from its attractiveness, and also so that garments or other articles wherein both sides are occasionally or commonly exposed may present an attractive appearance regardless of which side is exposed. Particular attractiveness can often be obtained in this manner when the design appearing on one side carries out the same general motif as the design appearing on the other side but is different in specific character. Such fabrics, moreover, are adapted for use in situations where it is now common practice to use a double fabric for the purpose under consideration, and, when so used, have the advantages of lightness in weight, unity of construction, and economy of production. Moreover, design portions having a distinctly outlined contour, and a less distinctly stressed—but nevertheless significant—center, are highly desirable in knitted fabrics.

Furthermore, the provision of design portions having a solidity of design, and in many instances design portions having a compactness—and often a bulkiness—which contrasts with the body of the fabric are desirable for many uses.

It is also desirable in many instances that there be provided design effects at certain points or portions, and that these be connected by yarn portions which extend on a particular side of the fabric where they can be utilized to carry out the design, or can be readily treated, or even eliminated if desired.

It is moreover desirable that designs be provided by warp yarn which is caught into the fabric particularly firmly, but which nevertheless give a linear design effect.

With the foregoing and other considerations in view, the present invention contemplates the provision of various novel types of fabric embodying features satisfying all or some of the foregoing needs, certain of such forms of fabric being particularly exemplified.

It is also desirable in a number of instances, and especially where a design-producing yarn is much heavier than the body yarn, that the former yarn be caught against the fabric at points which are relatively widely spaced.

The "design" or other ornamental-effect-producing yarn employed, while it may be the same character as the body yarns, or as one of the body yarns, employed, is ordinarily of a different color or of other different character, and may be composed of any of a wide variety of materials including special elastic yarns such as those known as "Lastex."

In the embodiment of the invention illustrated in Figs. 1, 2, and 3, there is provided a form of fabric comprising body yarn 2 knitted substantially in the jersey fashion to form a piece of fabric, the portion of which illustrated in Fig. 1 comprises courses 10-36 and needle wales 250-261; the intervening sinker wales being unnumbered. It is to be noted in this connection that references to wales herein are intended to designate needle wales except where otherwise designated or indicated by the context. The body yarn 2 extends continuously coursewise of the fabric. In courses 17-23 there is provided supplemental body yarn 3, which likewise extends continuously coursewise thruout the fabric, but which, at least in the portion of the fabric illustrated, is unknitted, but is caught into the fabric, being, in the present instance, laid-in in such fashion as to be caught under the sinker loops.

In this connection it is to be noted that when a yarn is laid into the fabric by being caught under the sinker loops, it may be made to extend under various portions of the sinker loops depending upon the looseness or tightness of the yarn laid-in and other factors, and that it may be so laid-in that it extends down under one sinker loop and up under another and then down under the next and up under the next, or that it may be floated over certain wales so as to be caught in various spaced wales as desired; and that, except as may be defined by the appended claims, the invention is not limited to any particular manner of laying-in a yarn or of otherwise catching it into the fabric without knitting.

In addition to the body yarn which forms the ground fabric, there is provided one or more additional yarns which in the present instance are warp yarns, and are desirably of a different color and/or character than the body yarns. One such yarn is exemplified at 4. If the ground yarns 2 and 3 are light-weight white yarns, or white and blue yarns respectively, the yarn 4 may be a heavy red yarn. This yarn is so embodied in the fabric as to provide design portions, a part of one design portion being shown at A, and other design portions being shown at B, C, and D. In these design portions, the yarn 4 extends back-and-forth over a limited area at one side (the rear) of the fabric and is knitted in proximity to at least certain of the edges of said area, being in the present instance knitted at both of the edges of the areas A, B, C, and D.

In the area A, it will be seen that the yarn 4 is knitted in wales 254 and 258 of course 10, and is intermediately laid-in by being extended under the sinker loops at each side of needle wale 256. In course 11, it is knitted in wales 255 and 257; and in course 12 it is knitted in wale 256. From this point it extends vertically at 5 at the rear of the fabric in the present instance, across courses 13, 14, 15, and 16, and is then knitted in

wale 256 of course 17 to form the beginning of the design portion B. In each of courses 18 and 22 it is knitted in wales 255 and 257, in each of courses 19 and 21 in wales 254 and 258, and in course 20 in wales 253 and 259. In course 23 it is knitted in wale 256, whence it extends downwardly at 6. In courses 20, 21, and 22, the extents of the yarn 4 between the points where it is knitted is laid into the fabric by being caught under the sinker loops. In each of courses 20 and 22 it extends under the sinker loops at each side of wale 256, in course 21 it extends under the sinker loops at each side of wale 255 and at each side of wale 257.

As will be appreciated, yarn may be otherwise arranged in accordance with this feature of the invention. In area C the design is more open vertically. Here the yarn is knitted in wales 253 and 259 in course 25, extending at the rear of the fabric from the latter point to the former point, and being caught under the sinker loops at each side of wales 257 and 255. Instead of being knitted in course 26, however, it extends downwardly from the loop in wale 253 of course 25 to be knitted in wale 252 in course 27, and thence extends at the rear of the fabric to the right, being caught under the sinker loops at each side of wales 254, 256 and 258 whereupon it is again knitted in wale 260. Thence it extends downwardly across course 28 to be knitted in wale 261 of course 29, and thence extends to the left, being caught under the sinker loops at each side of wales 260, 258, 256, 254, and 252.

In the area D there is provided a design portion which continues the design portion C, but wherein the yarn 4 is less tightly caught-in in its laid-in portion, such a type of catching-in of the design yarn being particularly advantageous when the design yarn is particularly heavy, as compared to the body yarn. In the portion D the yarn 4 is knitted in wale 250 in courses 31, 33, and 35, and in wale 261 in the same courses. In course 31 the laid-in portion of the yarn is caught under the sinker loops in the sinker wales at the left of needle wale 253, at the right of needle wale 254, at the left of needle wale 257 and at the right of needle wale 258. In course 33 it is laid under the sinker loops at the left of wale 251, at the right of wale 252, at the left of wale 255, at the right of wale 256, at the left of wale 259, and at the right of wale 260. In course 35, it is laid-in in an even looser fashion horizontally, being caught under the sinker loop at the left of wale 254 and under the sinker loop at the right of wale 257.

The yarn 4 thus extends back-and-forth and is generally at one side (the rear) of the body-fabric formed by the body yarn 2, and is caught into the fabric without knitting intermediate the edges of the design portion at which it is knitted. It is to be observed that, in the present instance, the body yarn 2 is unknitted at the points where the yarn 4 is knitted. For example, in course 18 the knitting of the yarn 2 is omitted in wales 255 and 257, the yarn 2 extending laterally from wale 254 to wale 256 and from wale 256 to wale 258, as indicated at 7 and 8, respectively.

Vertically extending portions, such as those at 5 and 6, may be left in place or cut away, as desired.

This type of embodiment of a warp or other design yarn in a fabric results in the provision of a reversible fabric wherein there is a design of one character on the front of the fabric, as indicated at A' and B' in Fig. 2; and a design

of a different character on the rear of the fabric, as illustrated at A and B in Fig. 3. There are thus provided fabrics either side of which may be used as the exposed side of a garment or other article, and which may be utilized with exceptionally pleasing results in cases where parts of the fabrics are turned over in the formation of a garment, or where the fabrics are to be used in garments, scarves, and other articles which may show from both sides during use. It is to be noted that the designs at A' and B' comprise the loops x at the edges of the design portion, and, in the present instance, also comprise points indicated at y at the interior of the design where the heavy yarn 4 shows at the front of the fabric as it passes under the sinker loops.

It will be appreciated that the design or other additional yarn may extend back-and-forth in a variety of other manners and may be caught into the fabric in a variety of other ways. Certain of these variations are exemplified in Fig. 4. One feature involved in the provisions of additional yarn which extends back-and-forth and wherein a conformation extending in one direction is caught into the fabric in the same course of knitting as a conformation extending in the other direction. In the form of fabric exemplified, the ground fabric comprises a body yarn 44 (which may be light-weight white yarn), and which is knitted substantially in the jersey fashion, as exemplified, to provide a piece of fabric including courses a—r and wales 264—285. A warp yarn 45 (which may be heavy red yarn) is incorporated in the fabric, as during its formation, to provide design areas E, F, and G. As will be seen, the yarn 45 extends vertically at 46, at the rear of the fabric in the present instance, past courses a and b, and is knitted to form a loop 47 in wale 276. In the present instance, this loop 47, instead of replacing a loop of the body yarn 44 as in Fig. 1, is provided between the loops of body yarn in courses c and d in wale 276. From the loop 47, the yarn 45 extends, at the rear of the fabric, downwardly and slightly to the right of Fig. 4, and then turns to the left where it is caught into the fabric in course d under the sinker loops at the left of wale 277, and continues to the left, being caught under the sinker loop at the right of the wale 275. It is knitted to form a loop 48 in wale 274 between the loops of the yarn 44 in courses d and e, and thence extends to the right in course d, being caught under the sinker loop at the right of wale 274, under sinker loops at each side of wale 276, thence under the sinker loop at the left of wale 278, and then is knitted to form a loop 49 in wale 278 between the loops of wale 44 in courses d and e. Thence it extends downwardly and slightly to the right, and then, extending to the left in course e, is caught under the sinker loops at the left of wale 279, and at each side of each of wales 277 and 275, and at the right of wale 273. Then it is looped in wale 272, and then extends to the right in course e, being caught under the sinker loop at the right of wale 272 and under the sinker loop at each side of each of wales 274, 276, and 278, and at the left of wale 280, when it is again looped in wale 280. Thereafter it extends to the left in course f under the sinker loop at the left of wale 279, under the sinker loop at each side of wale 277, and under the sinker loop at the right of wale 275; whereupon it is again looped (in wale 274) and extends to the right in course f, being caught under the sinker loop at the right of wale 274, under sinker loops at each side of the

wale 276 and under the sinker loop at the left of wale 278. It is knitted to form a loop (in wale 278) at this point, after which it is looped in wale 276, at the completion of the design portion E. Each of the loops of the yarn 45, are, as will be noted, intermediate loops of the body yarn 44.

From the loop in wale 276 above course g, the yarn 45 extends downwardly across the rear of the fabric, in the present instance, to wale 280 where it is again looped between courses j and k of the body yarn 44. Thence it repeats the general arrangement in portion E to provide an additional design portion F. It is to be noted that in the portion F, however, the yarn 45 is caught in adjacent sinker wales in its downward undulations, but is, in general, floated over three wales in its upward undulations. For example, in its leftward conformation in course j after it extends under the sinker loop at the left of wale 280, where it has been knitted between the loops of the yarn 44 in courses j and k, it is caught under the sinker loops at each side of wale 276, but is floated over wales 279—277 and over wales 275—273; and in its rightward conformation in course j after it is extended under the sinker loop to the right of wale 272 from the point where it is knitted in wale 272, it is caught under the sinker loops at each side of each of the wales 274 and 278 but is floated over wales 275—277. Similarly it is floated over three wales between the points where it is caught in both its leftward and rightward conformations in courses k, l, and m, being knitted at the edges in wales 270 and 282, wales 268 and 284, and wales 268 and 284, respectively. By floating it in this manner, less abrupt undulations are provided.

The yarn 45 extends downwardly and to the right across course n from the point wherein it is caught under the sinker loop at the right of wale 283 in course m. It is knitted between the loops in courses o and p in wales 268 and 288, and is, in general, caught under spaced sinker loops between these points, being caught, in the present instance, under the same sinker loop in both its forward and return extents, except that it undulates oppositely. As will be seen, it is caught under the sinker loops at the right of wales 269, 272, 275, etc. After extending to the right in course o, the yarn 45 extends downwardly and slightly to the right to be knitted in wale 287 between the loops of the yarn 44 in courses q and r. The yarn 45 is also similarly knitted in wale 265. In its forward and return conformations, it is caught under spaced sinker loops, but the sinker loops in this instance are different ones, tho the undulations are similarly rather than oppositely disposed. As will be seen, the leftward conformation extends under the sinker loops in course q at the right of wales 276, 272, 269, and 265, among others, and its rightward conformation extends under the sinker loops at the right of wales 268, 269, 273, 275, etc. In the present instance, the conformations of the yarn in and near courses o and q form a design portion G. It will be apparent that by means of such arrangements a wide variety of attractive effects may be secured in individual or various design portions.

In Fig. 5 there is shown a form of fabric providing design portions H and I each generally similar to the design portion E of Fig. 4, but connected by a vertical extent of warp yarn which extends on the front of the fabric rather than on the rear thereof, and further differing therefrom in that at one side of the area certain un-

knitted portions of yarn are provided beyond the loops thereof at that side. In the piece of fabric shown, the body yarn 48 (which may be similar to the yarn 44) is knitted to form courses 49—57 and wales 289—298. A warp yarn 58 (which may be similar to the yarn 45) is arranged in and above courses 49—52 similarly to the way the yarn 45 is arranged in and above courses 1—h except that in those courses where the right-hand loop is disposed to the left of a right-hand loop in the course next above it, the yarn extends from the latter loop downwardly and to the right across the wale at the right of the latter loop, where it is caught under the sinker loops at both sides of this wale and is thereafter caught at the sinker loops at both sides of alternate wales, if any, to the left until it reaches the wale to the right of the wale wherein it is knitted, where it is caught under the sinker loop to the right of this wale. For example in course 51, the yarn 57, after extending downwardly and to the right from the loop between courses 49 and 50 in wale 291, is caught under the sinker loops at each side of wale 298 and then under the sinker loops at both sides of each of wales 296 and 294, and then under the sinker loop at the right of wale 292, being thereupon knitted in wale 291 between course 50 and 51. In and above courses 56 and 57, the yarn 58 is arranged similarly to the manner in which the yarn 45 is arranged in and above courses d and e, except that the yarn coming down and to the right from the loop between courses 55 and 56 extends under the sinker loop at the right of wale 294 in course 56, and then upwardly under the sinker loop at the left thereof. Between the courses 51 and 55, the yarn 58 is carried on the front of the fabric, as indicated at 58a, where it will leave the design effect on the rear of the fabric substantially unconnected, but where it may connect the designs on the front of the fabric, or, if it is to be eliminated, will be in position for ready removal when the fabric is finished for use in a usual manner.

As above indicated, the invention, in certain of its aspects, contemplates the provision of various types of fabric wherein both the advance and return extents of an auxiliary yarn are laid into the same course of knitted yarn. A form of fabric of this character, which is generally similar to the fabric of Figs. 4 and 5, except that the auxiliary yarn is not knitted, is shown in the process of formation in Fig. 6, and is illustrated diagrammatically in Fig. 7, a portion thereof being illustrated in greater detail in Fig. 8. As will be seen from these figures, the piece of fabric exemplified comprises a body yarn 59 knitted in the jersey fashion to form courses including courses 60, 61, 62, and 63, and wales including wales 300—316. A design formation J is provided by a warp yarn 64. An advance extent 65 of the yarn 64 is laid into the fabric in course 62 of the knitted yarn, and a return extent 66 is laid into the same course 62, the advance extent of the yarn being laid in front of different needles than the return extent of the yarn, and consequently having contiguous portions caught under the sinker loops at the sides of different needle wales. Similarly, in a succeeding course 63 of the knitted body yarn 59, an advance extent 67 and a return extent 68 of the auxiliary yarn 64 is laid into the fabric. From the extent 65, the auxiliary yarn extends at the front of the fabric past one or more courses, such as the courses 60 and 61. In the particular arrangement exem-

plified, the undulations are only one wale in width.

In Fig. 9 there is shown a form of fabric wherein a body yarn 88 (which may be blue ground yarn) is knitted thruout the fabric, except that occasionally, as hereinafter pointed out, a loop of an additional yarn is knitted in place of a loop of the yarn 88. A supplemental ground yarn 81 extends coursewise and is caught into the fabric at spaced wales (alternate wales in the present instance) between a loop in one row and a loop in an adjacent row to provide a modified jersey fabric. As exemplified, the yarn 81 (which may be white yarn) is caught under the sinker loops at each side of each of wales 501, 503, etc., and is carried entirely at the rear of the fabric at wales 500, 502, etc. A strand of additional yarn 82 (which may be red yarn which is heavier than the yarns 88 and 81) is incorporated in the fabric to provide a loop 82a in place of a loop of the yarn 88 at wale 501 of course 172. The yarn 82 extends at the rear of the fabric diagonally upwardly and to the right from this loop to a point wherein it is caught in the fabric at a point above the showing of the figure; and extends at the rear of the fabric diagonally downwardly to the right to a point 82b where it is formed into a loop in place of a loop of the yarn 88 in wale 503 of course 175; thence at the rear of the fabric again downwardly to the right to a point 82c where it forms a loop in place of a loop of the yarn 88 in wale 505 of course 177; thence at the rear of the fabric downwardly to the left to form a loop 82d in place of the loop of the yarn 88 in wale 502 of course 182; and thence at the rear of the fabric downwardly to the right to a further point (not shown) where it is caught into the fabric.

Another additional yarn 83 (which may also be heavy red yarn, altho it may be yarn of still another character, if desired) extends at the front of the fabric downwardly from an upper point (not shown), wherein it is caught into the fabric, to a point 83a wherein it forms a loop replacing the loop of the body yarn 88 in wale 507 of course 172; thence at the rear of the fabric laterally and somewhat downwardly, in the present instance, to a point 83b wherein it forms a loop in wale 511 of course 174; thence at the front of the fabric downwardly to a point 83c where it forms a loop in wale 511 of course 180; thence laterally and somewhat downwardly at the rear of the fabric, in the present instance, to a point where it forms a loop in wale 508 of course 183; and thence downwardly at the front of the fabric to a lower point (not shown) where it is again caught into the fabric.

In Fig. 10 there is shown a form of fabric wherein the only ground yarn is the body yarn 98 (which may be similar to the yarn 88 of Fig. 9) which is knitted thruout the fabric except that occasionally, as hereinafter pointed out, a loop of additional yarn is knitted in place of a loop of the yarn 98. The yarn 98 is knitted to form wales 512 thru 520 and courses 180 thru 204. The additional yarn 91 (a warp yarn which may be similar to the yarn 83 of Fig. 9) extends at the front of the fabric downwardly from an upper point (not shown), wherein it is caught into the fabric, to a point 91a, wherein it forms a loop replacing the loop of the body yarn in wale 514 of course 194; thence at the rear of the fabric laterally to wale 518, being caught, in the present instance, under the sinker loops at each side of wale 516. It forms a loop 91b at

this point, and thence extends at the front of the fabric downwardly to course 199, where it extends to the left at the rear of the fabric, being then knitted at point 91c to form a loop in wale 517 of course 200; thence it extends further to the left at the rear of the fabric to the point 91d where it forms a loop in wale 515 of course 200 and thence downwardly to a lower point (not shown) where it is again caught into the fabric.

A second warp yarn 92 (which may be heavy green yarn) appears in Fig. 10. It extends vertically at the front of the fabric thru course 192, where it is knitted in wale 519. It then extends to the right in an undulating manner being caught under the sinker loops at each side of wale 521. It then extends vertically downward at the front of the fabric between wales 522 and 523, and is knitted in course 194 in wale 523. It then extends vertically downward in the front of the fabric to course 200 where it is again knitted in wale 523. It then extends at the rear of the fabric past wales 522 and 521, and thence runs vertically downward to course 203 where it is knitted in wale 520.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. A knitted fabric comprising a multiplicity of courses of knitted yarn, and other yarn extending back-and-forth in a portion of the fabric to provide a plurality of forward and return conformations, each of a plurality of said conformations being laid into the fabric in a single course.

2. A knitted fabric comprising body yarn knitted to form a multiplicity of courses and wales, and additional yarn extending back-and-forth across a limited number of said wales in a portion of said fabric, a number of the forward and rearward parts of the conformation of said additional yarn providing substantially coursewise extents of additional yarn caught into the fabric in said portion without knitting, and a plurality of such extents being caught into the fabric in one of said courses.

3. A knitted fabric comprising body yarn knitted to form a multiplicity of courses and wales, and additional yarn extending back and forth across a limited number of said wales in a portion of said fabric, a number of the for-

ward and rearward parts of the conformation of said additional yarn providing substantially coursewise extents of additional yarn caught into the fabric in said portion without knitting, and a plurality of such extents being caught into the fabric in each of a plurality of said courses.

4. A knitted fabric comprising body yarn knitted to form a multiplicity of courses and wales, and additional yarn extending back and forth across a limited number of said wales in a portion of said fabric, a number of the forward and rearward parts of the conformation of said additional yarn providing substantially coursewise extents of additional yarn caught into the fabric in said portion without knitting, and a plurality of such extents being caught into the fabric in each of a plurality of adjacent ones of said courses.

5. A knitted fabric comprising body yarn knitted to form a multiplicity of courses and wales, and additional yarn extending back-and-forth across a limited number of said wales in a portion of said fabric, a number of the forward and rearward parts of the conformation of said additional yarn providing substantially coursewise extents of additional yarn caught into the fabric in said portion, and said additional yarn being also knitted into said fabric at certain points thruout its back-and-forth conformation in said portion, and a plurality of such extents being caught into the fabric in one of said courses.

6. A knitted fabric comprising body yarn knitted to form a multiplicity of courses and wales, and additional yarn extending back-and-forth across a limited number of said wales in a portion of said fabric, a number of the forward and rearward parts of the conformation of said additional yarn providing substantially coursewise extents of additional yarn caught into the fabric in said portion, and said additional yarn being also knitted into said fabric at points approximately where said conformation changes direction, and a plurality of said extents being caught into the fabric in at least one of said courses.

7. A knitted fabric comprising body yarn knitted to form a multiplicity of courses and wales, and additional yarn extending back-and-forth across a limited number of said wales in a portion of said fabric, a number of the forward and rearward parts of the conformation of said additional yarn providing substantially coursewise extents of additional yarn caught into the fabric in said portion, and said additional yarn being also knitted into said fabric at certain points thruout its back-and-forth conformation in said portion, and a plurality of said extents being caught into the fabric in each of a plurality of said courses.

VINCENT LOMBARDI.
